UNITED STATES PATENT OFFICE.

CHARLES MARSHALL GRAVATT, OF PORT ROYAL, VIRGINIA.

MARKING DEVICE.

1,353,742.

Specification of Letters Patent. Patented Sept. 21, 1920.

Application filed March 29, 1920. Serial No. 369,730.

To all whom it may concern:

Be it known that I, CHARLES M. GRAVATT, a citizen of the United States, and a resident of Port Royal, in the county of Caroline and State of Virginia, have invented a new and Improved Marking Device, of which the following is a full, clear, and exact description.

This invention relates to improvements in marking devices, an object of the invention being to provide a device of the character stated which is especially adapted for marking cloth or clothing of any character so as to identify the material or articles and 15 is especially adapted for use in connection with laundry work to distinguish the property of different customers.

A further object is to provide a marking device which is adapted to form a monogram or other identifying characters in the material and which monogram can be of any desired color and will withstand the laundry operation without affecting the same.

With these and other objects in view the invention consists in certain novel features of construction, and combinations and arrangements of parts, as will be more fully hereinafter described and pointed out in the 25 claims.

In the accompanying drawings—

Figure 1 is a view in vertical longitudinal section illustrating my improved device in one position;

Fig. 2 is a similar view showing the device in a different position;

Fig. 3 is a fragmentary plan view;

Fig. 4 is a view in section on the line 4—4 of Fig. 1;

Fig. 5 is a view partly in side elevation and partly in vertical section illustrating a modification;

Fig. 6 is a view in section on the line 6—6 of Fig. 5; and

Fig. 7 is an enlarged perspective view of a die.

1 represents a casing having a base 2 which may be rigidly secured to any approved support 3 and this casing 2 at its 50 lower forward end is recessed, as shown at 5, to provide an entrance for the goods to be marked. 6 represents a vertically movable elevator which is mounted in the casing 1 and is adapted to be locked in elevated position by means of a spring held bolt 7 on top of the casing engaging in a notch 8 in

the elevator whenever it is desired to hold the elevator against movement to manipulate the parts thereof, as will be readily understood.

The elevator 6 is formed with a reservoir 9 which is of general cylindrical shape throughout the greater portion of its length and is adapted to receive a composition 10 for marking the goods. This composition is 65 of a plastic nature and may be of any desired color. It is of such form that when exposed to the air or to heat, will harden and have the general appearance and properties of celluloid.

The lower end of the reservoir 9 is made with a restricted outlet 11 normally registering with an opening 12 in a slide plate 13. This plate 13 is supported and held in operative position against the lower 75 end of the elevator by means of a bottom plate 14 secured to the bottom of the reservoir and having a suitable groove or recess therein for the accommodation of the plate 13. A plunger 15 is mounted in the upper 80 portion of the reservoir 9 and is provided with a stem 16 projecting through a removable cover 17 of the reservoir and a coiled spring 18 is located around the stem between the cover 17 and the plunger 15 exerting a 85 sufficient pressure on the composition to eject the same when permitted by the plate 13. The cover 17 preferably has screw-threaded engagement with the reservoir 9 as shown at 19, and is made with spanner 90 receiving notches 20 in its outer face.

The elevator 6 is made in its upper portion with a bore 21 and in its lower portion with a bore 22 of appreciably less diameter than the bore 21 and said bore 22 is of the 95 same diameter as the opening 12 in plate 13 and is located in alinement with an opening 23 in the bottom plate 14. A plunger 25 is mounted in the larger bore 21 and has a reduced lower end 26 movable in the reduced 100 bore 22. A coiled spring 27 is located around the reduced end 26 of plunger 25 and is housed in the bore 21 so as to exert upward pressure on the plunger 25 normally holding said plunger in elevated position. A screw 28 in the elevator 6 projects into a longitudinal groove 29 in the plunger 25 to limit the longitudinal movement of the latter and an enlargement 30 is provided on the upper end of the plunger 25 110 to facilitate its operation.

The reduced end 26 of the plunger 25 is

made with a dove-tailed recess 31 to receive a dove-tailed tenon 32 on a die 33 to removably connect the die to the plunger. This die fits within the reduced bore 22 of the elevator 6 and is movable through the openings 12 and 23 to eject the composition and force it into the goods.

A platen 34 is located below the plunger and supported by the base 2. This platen 34 preferably has a screw threaded shank 35 screwed into a threaded opening 36 in the base 2 and is made with spanner receiving notches 37 to receive a spanner wrench and permit its vertical adjustment. A screw 38, 15 which is similar in construction to the platen 34, is adjustably located in a screw threaded opening 39 in the base 2 below a circular enlargement 40 on the bottom plate 14, and a coiled spring 41 is located between the 20 plate 14 and the base 2 and is centered by means of the enlargement 40 and the screw 38. This spring 41 exerts an upward pressure on the elevator tending to elevate the same and is weaker than the spring 27 so 25 that it is compressed before the spring 27 is compressed, as will more fully hereinafter appear.

A bell crank lever 42 has a slot and pin connection 43 with the casing 1 and at its 30 angle is connected by a pivot 44 between two arms 45 projecting from the elevator 6. The lower end of the lever 42 has a slot and pin connection 46 with the plate 13 and a set screw 47 is projected through the end 35 wall of casing 1 and limits the movement of this lever in one direction, as shown in Fig. 1, which limits the upward movement of the elevator.

In the modification shown in Figs. 5 and 6 40 I illustrate a bow spring 48 between the lever 42 and the elevator 6 which operates to raise the elevator and takes the place of the spring 41 in the preferred form. In this modification I also illustrate a plunger 45 49 on top of the composition 10 which is pressed downwardly by a coiled spring 50 engaged by a disk 51 on the lower end of a stem 52. This stem 52 is provided at one 50 edge with a series of ratchet notches 53 which are engaged by a spring finger 54 on the plunger 25 so that at each operation of the plunger, the stem 52 will be moved downwardly to put the spring 50 under compression. A frail ratchet spring 55 is 55 mounted in the cover 56 of the reservoir and projects through a slot 57 therein and this spring holds the stem 52 against upward movement. The finger 54 is relatively weak so that when the spring 50 is under the desired 60 compression, the finger 54 will ride over the ratchet notches 53 in both directions and will move the stem downwardly only after the spring 50 is expanded. The purpose of this construction is to maintain 65 the spring 50 under a suitable compression

sufficient to eject the composition 10. When it is desired to release the stem, the outwardly projecting end of the ratchet spring 55 can be manually moved to one side as will be readily understood.

Referring particularly to Figs. 1 and 2, the operation of my improved device is as follows: The material, not shown, to be marked is inserted in the recessed portion 5 and located above the platen 34. A downward pressure is applied to the plunger 25 and as the spring 41 is weaker than the spring 27, this spring 41 will first be compressed allowing the elevator 6 to move downwardly. As the elevator 6 moves 80 downwardly, the movement of the lever 42 will compel the plate 13 to move forwardly positioning the opening 12 therein in alignment with the bore 22 and the opening 23. The adjustment of a screw 38 controls 85 downward movement of elevator 6 and forward movement of plate 13, thereby insuring exact alignment of opening 12 with plunger 26. At the same time this plate 13 effectually cuts off or closes the lower end of 90 the reservoir 9. A continued downward pressure of the plunger 25 will compress the spring 27 forcing the die 33 through the opening 23 of bottom plate 14 carrying with it the composition which had been located in 95 the opening 12 and pressing this composition into the material above the platen 34. When pressure on the plunger 25 is released, the springs 41 and 27 will return the parts to normal position.

As above stated, I employ a composition which will harden when exposed to the air or heat and which will impregnate the cloth or other material and form a monogram or other suitable identification mark to identify the material, and which will withstand the laundry operation.

When it is desired to refill the reservoir, the bolt 7 is moved into the notch 8 locking the elevator in its downward movement. 110 The cover 17 and the plunger 15 can then be removed and the reservoir filled when said plunger and cover can be replaced and the device is ready for renewed operation.

When the die 23 is to be changed, the elevator 6 is locked in elevated position by means of bolt 7 and the plunger 25 drawn out, after screw 28 is withdrawn, when the die can be replaced.

The die is preferably made in three pieces, 120 each containing separate characters, so that any monogram can be formed.

Various slight changes might be made in the general form and arrangement of parts described without departing from the invention, and hence I do not limit myself to the precise details set forth, but consider myself at liberty to make such changes and alterations as fairly fall within the spirit and scope of the appended claims.

I claim:

1. A device of the character stated, comprising a casing, a movable elevator in the casing having a reservoir therein, a plunger in the elevator, and means operated by the movement of the elevator to transfer material from the reservoir into position below the plunger. 5
2. A device of the character stated, comprising a casing, a movable elevator in the casing having a reservoir therein, a plunger in the elevator, means operated by the movement of the elevator to transfer material from the reservoir into position below the plunger, and a bottom plate on the elevator having an opening therein registering with the plunger. 10
3. A device of the character stated, comprising a casing, a movable elevator in the casing having a reservoir therein, a plunger in the elevator, means operated by the movement of the elevator to transfer material from the reservoir into position below the plunger, a bottom plate on the elevator having an opening therein registering with the plunger, and an adjustable platen below said opening. 15
4. A device of the character stated, comprising a casing, a movable elevator in the casing having a reservoir therein, a plastic composition in the reservoir, a plunger in the elevator, a sliding plate having an opening therein normally registering with the reservoir and receiving the composition therein, and means operated by the movement of the elevator in one direction to move said plate cutting off the reservoir and positioning the said opening with the composition therein in alinement with the plunger. 20
5. A device of the character stated, comprising a casing, a movable elevator in the casing having a reservoir therein, a plastic composition in the reservoir, a plunger in the elevator, a sliding plate having an opening therein normally registering with the reservoir and receiving the composition therein, a spring normally holding the elevator in elevated position, a spring normally holding the plunger in elevated position and stronger 25 than the first-mentioned spring, a bottom plate on the elevator guiding the first-mentioned plate and having an opening therein in line with the plunger, a platen below said last-mentioned opening, and a lever compelling the movement of the first-mentioned plate to position the opening therein above the last-mentioned opening when the elevator is depressed. 30
6. A device of the character stated, comprising an elevator having a reservoir therein, a plunger in the elevator, a transfer device adapted to convey a predetermined quantity of material from the reservoir into position below the plunger, a lever pivotally connected at one end to the casing and at its 35 other end to said transfer device, two arms on the elevator pivotally connected to the intermediate portion of said lever, a spring exerting upward pressure on the elevator, and a set screw in the casing limiting the movement of the lever in one direction. 40
7. A device of the character stated, comprising a casing, a movable elevator in the casing having a reservoir therein, a plunger in the elevator, means operated by the movement of the elevator to transfer material from the reservoir into position below the plunger, a plunger in the reservoir, a spring in the reservoir exerting downward pressure on the plunger, a stem on the plunger projecting above the reservoir, a removable cap on the upper end of the reservoir, and a spring held bolt adapted to engage the elevator and hold the same in elevated position. 45
8. A device of the character stated, comprising a casing, a movable elevator in the casing having a reservoir therein, a plunger in the elevator, means operated by the movement of the elevator to transfer material from the reservoir into position below the plunger, a bottom plate on the elevator having an opening therein registering with the plunger, a plunger in the reservoir, a spring in the reservoir exerting downward pressure on the plunger, a stem on the plunger projecting above the reservoir, a removable cap on the upper end of the reservoir, and a spring held bolt adapted to engage the elevator and hold the same in elevated position. 50
9. A device of the character stated, comprising a casing, a movable elevator in the casing having a reservoir therein, a plunger in the elevator, means operated by the movement of the elevator to transfer material from the reservoir into position below the plunger, a bottom plate on the elevator having an opening therein registering with the plunger, an adjustable platen below said opening, a plunger in the reservoir, a spring in the reservoir exerting downward pressure on the plunger, a stem on the plunger projecting above the reservoir, a removable cap on the upper end of the reservoir, and a spring held bolt adapted to engage the elevator and hold the same in elevated position. 55
10. A device of the character stated, comprising a casing, a movable elevator in the casing having a reservoir therein, a plunger in the elevator, means operated by the movement of the elevator to transfer material from the reservoir into position below the plunger, an enlargement on the upper end of the plunger, said plunger having a longitudinal groove therein, a screw projected through the elevator into said groove and limiting the movement of the plunger, and an adjustable stop secured to the base of the casing and limiting the downward movement of the elevator. 60

11. A device of the character stated, comprising a casing, a movable elevator in the casing having a reservoir therein, a plunger in the elevator, means operated by the movement of the elevator to transfer material from the reservoir into position below the plunger, a bottom plate on the elevator having an opening therein registering with the plunger, an enlargement on the upper end 10 of the plunger, said plunger having a longitudinal groove therein, a screw projected through the elevator into said groove and limiting the movement of the plunger, and an adjustable stop secured to the base of the 15 casing and limiting the downward movement of the elevator.

12. A device of the character stated, comprising a casing, a movable elevator in the casing having a reservoir therein, a plunger in the elevator, means operated by the movement of the elevator to transfer material from the reservoir into position below the plunger, a bottom plate on the elevator hav-

ing an opening therein registering with the plunger, an adjustable platen below said 25 opening, an enlargement on the upper end of the plunger, said plunger having a longitudinal groove therein, a screw projected through the elevator into said groove and limiting the movement of the plunger, and an adjustable stop secured to the base of the 30 casing and limiting the downward movement of the elevator.

13. A device of the character stated, comprising a casing, a vertically movable elevator in the casing, a reservoir in the casing adapted to contain a plastic composition, a plunger in the elevator having a dove-tailed recess in its free end, a die having a dove-tailed tenon located in said recess, and means 35 for transferring a quantity of said composition from the reservoir into position under the die when the elevator is moved in one direction.

CHARLES MARSHALL GRAVATT.
